UNITED STATES PATENT OFFICE.

JAMES GLENNON, OF ROCHESTER, MINNESOTA.

DIRIGIBLE HEADLIGHT.

1,300,720.

Specification of Letters Patent.

Patented Apr. 15, 1919.

Application filed July 5, 1918. Serial No. 243,421.

To all whom it may concern:

Be it known that I, JAMES GLENNON, a citizen of the United States, residing at Rochester, in the county of Olmsted and State of Minnesota, have invented a new and useful Dirigible Headlight, of which the following is a specification.

This invention relates to dirigible headlights for automobiles, one of its objects being to provide operating mechanism for headlights of this character which is simple and efficient, will operate smoothly and with the minimum friction, and which will not interfere with or be broken by the movement of the chassis relative to the running gear.

Another object is to provide operating mechanism having its moving parts supported and guided by improved means provided for that purpose.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of parts without departing from the spirit or sacrificing any of the advantages of the invention as set forth in the appended claims.

In the accompanying drawings the preferred form of the invention has been shown.

In said drawings

Figure 1 is a front elevation of a portion of an automobile having the present improvements applied thereto.

Fig. 2 is a side elevation thereof.

Fig. 3 is a vertical section through the bearings of one of the posts of the lamps.

Fig. 4 is a section on line 4—4, Fig. 3.

Fig. 5 is a section through the slideable connection between the upper and lower portions of the operating mechanism of the headlights.

Fig. 6 is a plan view of the connection between one of the knuckles of a steering or front wheel and the cross rod.

Fig. 7 is a section on line 7—7, Fig. 1.

Fig. 8 is a section on line 8—8, Fig. 1.

Referring to the figures by characters of reference, A designates the front axle of an automobile and K the knuckles thereof which are connected and operated in the usual manner. An arm 1 is extended for-

wardly from one of the knuckles and has one end of a rod 2 pivotally connected thereto. This rod is provided with spaced blocks 3 which are slidably mounted in guide housings 4 secured to brackets extending forwardly from the axle A as shown at 5.

An arm 6 extends upwardly from the center of the rod 2 and has its upper portion bent forwardly to form an eye 7. The forwardly extended portion is adapted to work within a slot 8' extending longitudinally within the back portion of a tubular housing 8, there being balls 9 in the eye 7 within the housing and bearing outwardly against the wall of the housing.

The housing 8 is connected to and supported by a rod 10 the ends of which are slideable within housings 11 secured on the springs S of the automobile. The same arrangement may be provided within these housings as in the housings 4 friction being reduced in both housings, if desired, by anti-friction balls or rollers 12 interposed between the bottoms of the housings and the movable members therein.

Lamp supporting brackets are extended laterally and upwardly from the sides of the radiator R of the automobile, as shown at 13, and each of these brackets has a cylindrical housing 14 formed of a fixed section 15 and hinged or door sections 16. The section 15 has superposed disks 17 secured thereto and each provided with a central upwardly extending boss 18. Each boss has a race for a series of antifriction balls 19 or the like on which a cap 20 is supported for rotation. The caps are secured to and rotate with a stem or post 21 the upper end of which is connected to and supports a lamp 22 while the lower end has a crank arm 23. A rod 24 is connected at its ends to these crank arms and at its center to the top of the housing 8. A brace rod 25 may be extended between and secured to the housings 14.

It will be apparent that when the chassis of the automobile moves relative to the running gear by reason of the springs S supporting the same, the housing 8 will work upon the arm 6. Any longitudinal movement of the rod 2 caused by the turning of the front wheels W of the automobile will result in a side thrust against the housing 8 with the result that the rod 10 and rod 24 will be correspondingly moved, causing the

lamps to be rotated to throw the light rays in the direction in which the machine is turned.

By opening the housings the bearings therein can be cleaned and repaired readily. The various antifriction bearings cause the apparatus to operate easily.

What is claimed is:—

- 10 1. The combination with a motor vehicle, of a dirigible headlight attachment including a slideable rod, bearings therefor on the front axle of the vehicle, means for sliding the rod when the front wheels of the vehicle are turned, an upstanding arm on the rod, a housing slideable on the arm and shiftable laterally therewith, a ball bearing in said housing and carried by the arm, bearings on the springs of the vehicle, a supporting rod extending into said bearings and from the housing, revoluble lamp posts, bearings therefor, and a rod connecting the housing

Copies of this patent may be obtained for five cents each, by addressing the "Commissioner of Patents, Washington, D. C."

with the posts to rotate the posts during the lateral movement of the housing.

2. The combination with a motor vehicle, a laterally shiftable rod, and means for shifting the rod when the front wheels of the vehicle are turned laterally, of fixed brackets, a housing upon each bracket and including a fixed section and hinged sections, bearings carried by the fixed section, caps supported thereby, a post secured to and revoluble with the caps in each housing, a lamp connected to each post, a crank arm on each post, said arms being pivotally connected to the rod. 35

In testimony that I claim the foregoing as my own, I have hereto affixed my signature in the presence of two witnesses.

JAMES GLENNON.
